UNITED STATES PATENT OFFICE.

ANDREW BENSON, OF JANEVILLE, WISCONSIN, ASSIGNOR TO JANEVILLE PRODUCTS COMPANY, OF JANEVILLE, WISCONSIN, A CORPORATION OF WISCONSIN.

SHEET-METAL WHEEL AND THE LIKE AND PROCESS OF MAKING SAME.

1,303,236.

Specification of Letters Patent.

Patented May 13, 1919.

Application filed February 9, 1918. Serial No. 216,200.

To all whom it may concern:

Be it known that I, ANDREW BENSON, a citizen of the United States, residing at Janesville, in the county of Rock and State 5 of Wisconsin, have invented a certain new and useful Improvement in Sheet-Metal Wheels and the like and Processes of Making Same, of which the following is a full, clear, concise, and exact description, reference being had to the accompanying drawings, forming a part of this specification.

This invention relates to improvements in sheet metal wheels and the like and process of making same.

So far as I am aware, no one has heretofore been able to manufacture satisfactorily a sheet metal wheel having a hollow tubular rim formed integrally with spokes or other central section of the wheel from 15 a single sheet of metal, due to the inability to obtain a true tubular formation of rim by simply stamping and pressing of the rim.

One object of my invention is to provide 25 as an article of manufacture and process of making same, a sheet metal wheel having a hollow tubular rim or grip portion, which wheel is formed from a single sheet of metal by a novel series of stamping and die 30 pressing operations and wherein the tubular rim is of substantially true circular form in cross section throughout to thereby form a smooth gripping surface for the user.

Another object of the invention is to provide 35 as an article of manufacture and process, a sheet metal wheel of the character above indicated which can be obtained cheaply and by comparatively simple stamping and pressing operations.

In the drawing forming a part of this specification, I have shown my invention as carried out in the manufacture of a sheet metal wheel suitable for steering 45 children's wagons or carts, but as will be obvious to those skilled in the art, the uses to which the completed article may be put are numerous and I do not intend that the specific description herein contained shall 50 be construed in a limiting sense but rather as merely descriptive. It is evident, for instance, that the "wheels" which term is used generically throughout the specification

and claims to mean any article of like characteristics may be used for operating valves, 55 steam fittings, etc.

In said drawing, Figure 1 is a top plan view of a sheet of metal showing the same at the end of the first operation in carrying out the process. Fig. 2 is a sectional view 60 taken substantially on the line 2—2 of Fig. 1. Fig. 3 is a view similar to Fig. 1 illustrating the condition of the article at the end of the next or stamping step. Fig. 4 is an enlarged side elevational view of a 65 section of the rim flange portion of the article as shown in Fig. 3 and after certain notches have been cut therein. Fig. 5 is a view similar to Fig. 4 illustrating the condition of the rim flange portion at the end 70 of the next or die pressing operation. Fig. 6 is a detail sectional view taken substantially on the line 6—6 of Fig. 5. Fig. 7 is a sectional view of the wheel after the rim has been completely formed, the section 75 corresponding substantially to the line 7—7 of Fig. 3, although Fig. 3 is not intended to represent the article in the condition shown in Fig. 7. Fig. 8 is a view similar to Fig. 3 illustrating the completed wheel. 80 And Fig. 9 is a sectional view of the completed wheel taken substantially on the line 9—9 of Fig. 8.

In carrying out my invention, I first take 85 a sheet of metal of the desired gage, and with the same cut to the desired shape and size, I press the same so as to provide an annular depending rim flange 10 and a central dished or concaved portion 11, the rim flange 10 and central portion 11 being 90 united by a curved section 12. As shown most clearly in Fig. 9, the completed wheel has the spokes thereof offset downwardly 95 relatively to the horizontal plane defined by the rim and the central dished portion 11 shown in Fig. 2 is concaved to correspond to the desired offsetting above mentioned, as will be understood.

The article as shown in Fig. 2, is next 100 subjected to a stamping operation by which the sections corresponding to the spaces indicated at 13—13 in Fig. 3 are cut out, thus leaving a series of radial arms or spokes 14—14. During this same operation, the central portion of the disk or plate may be 105 punched as indicated at 15, so as to pro-

vide means, in the finished article, for suitably attaching the wheel to a post or other member. Also, during this step, the rim portion is bent so as to provide an upper 5 substantially semi-circular section, as indicated most clearly at 16 in Fig. 3. Said semi-circular section 16 is made somewhat less than a true semi-circle by leaving an interior narrow flange 17, as also indicated 10 in Fig. 3.

In the next step of the process, the marginal or rim flange 10 is cut with a series of tapered notches, as indicated at 18—18 in Fig. 4, these notches being spaced at equal 15 distances apart and being so designed as to compensate for the decreased circumference of the free edges 19 of the rim flange when said free edges 19 are brought to their final position, as shown in Figs. 7 and 9. The 20 depth of the notches 18 is made such that the notches, in the finished wheel, will become slits 120, as indicated in Figs. 7 and 9, which extend only from the lowest point of the rim. During this step also, the narrow 25 flange 17, referred to above in connection with Fig. 3, is bent to conform to the substantially semi-circular portion 16 to thereby complete the semi-circular section of the rim, as indicated at 116 in Fig. 6. That is, 30 the upper half of the wheel rim is completed at the end of the step illustrated in Fig. 4.

The next step in the process I consider radically new and the one which enables me to obtain a substantially perfect tubular annular rim in the completed article, and this 35 step consists in bending or die pressing each section 20 of the notched flange toward the center of the wheel or transversely, as indicated by the portion marked 21 in Fig. 6 and 40 in also bending or die pressing each section of the rim flange 20 lengthwise thereof so as to present a concave outer surface for each section 20, as indicated at 22 in Figs. 5 and 6. The double bending of the sections 20 of 45 the notched flange may be carried out simultaneously in actual practice. The curvature of the sections 20 as indicated at 21, that is, in a manner to complement the semi-circular section 116, is done to facilitate the final 50 curling or pressing of the rim into tubular form. The other bending of the notched flange portions, as indicated at 22, is made such that the radius of the concavity 22 will correspond to the radius from the center of 55 the finished wheel to the nearest portion of the completed tubular rim thereof. In other words, the free edges of the notched sections of the rim flange are bent, before the final formation of the rim, in such a manner 60 that said free edges become true sections of a circle corresponding to the inner circle of the annular rim. Were it not for the concaving of the sections 20 of the rim flange, said sections 20 in the completed 65 tubular rim would form a series of bulges

on the inner portion of the rim and the latter would not be of true circular cross section.

The next step in the process is illustrated by Fig. 7 and consists in completing the 70 curling or bending of the rim portion of the wheel so as to bring the free edges of the notched portions 20 to abut the inner edge 23 of the upper semi-circular section of the rim, this action completing the formation of 75 the tubular rim.

To provide additional strength in the spokes of the wheel and also to have the finished article present a better appearance, the wheel is finally subjected to a drawing 80 operation whereby the spokes are provided with ribs 24—24 and a boss at the center of the wheel, as indicated at 25.

From the preceding description, it will be 85 seen that with my invention I am enabled to manufacture a sheet metal spoked wheel having an integral tubular rim by a comparatively simple process and one which may be carried out in five steps to form the completed article illustrated in Figs. 8 and 90 9. It will also be noted that I avoid the use of flexible or collapsible cores in the formation of the rim.

While I have herein described the steps 95 as occurring in a certain sequence which I consider preferable, nevertheless it is evident that the sequence of some of the steps may be varied without departing from the spirit of the invention and also that various other changes and modifications may be employed 100 within the scope of the claims appended hereto.

I claim:

1. The herein described process which consists in; providing a sheet of metal stamped and pressed into circular form with the rim comprising a substantially semi-circular portion and a flange tangential thereto, said flange portion being notched at intervals along its free edge; bending the portion of 110 the flanges between the notches in a direction to continue the curvature of said semi-circular portion of the rim; bending each portion of said flange between pairs of notches to a concave form; and completing 115 the rim by bending said portions of the rim flange until the free edges thereof come into engagement with the inner edge of said semi-circular rim portion.

2. The process of manufacturing a sheet 120 metal wheel and the like which consists in; providing a sheet of metal stamped and pressed into circular form with the rim thereof comprising a substantially semi-circular portion and a flange tangential thereto, the flange being notched at intervals; then simultaneously bending the portions of 125 said flange between notches transversely and longitudinally of said portions; and completing the rim by bending said portions of 130

the rim portions transversely thereof until the free edges of said portions come into engagement with the inner edge of said semi-circular rim portion.

5 3. The process of manufacturing sheet metal wheels and the like which consists in; providing a sheet of metal stamped and pressed into circular form with the rim comprising a curved portion and a flange 10 portion, said flange portion being notched at intervals along its free edge; then die pressing each portion of said flange between pairs of notches longitudinally thereof so as to present an outer concave surface; and then 15 die pressing the flange portions of the rim so as to complete the circular cross section thereof.

4. The process of manufacturing sheet metal wheels and the like which consists in; 20 providing a sheet of metal stamped and pressed to a circular formation with a rim comprising a curved portion and a flange; notching said flange in its free edge to compensate for a smaller circumference when 25 the flange is subsequently bent; then bending said flange so as to bring the free edges thereof into contact with the inner edge of said curved portion of the rim.

5. The process of manufacturing sheet 30 metal wheels and the like which consists in; providing a sheet of metal of circular form having a central portion and a peripheral flange; cutting out sections of the central portion to thereby provide a series of radially extending spokes; notching said peripheral flange; and then curling said flange so as to bring the free edges of the notched portions inwardly and upwardly to the level of the central portion.

40 6. The process of manufacturing sheet metal wheels and the like which consists in; taking a sheet of metal and pressing the same so as to provide a central dished portion and a circular rim flange; cutting out sections 45 of said central portion to thereby provide spokes; notching said flange portion at intervals; bending each portion of said rim flange between a pair of notches in a direction lon-

gitudinally of each said portion; and finally bending said rim flange to a circular form in 50 cross section.

7. The herein described process of manufacturing sheet metal wheels and the like which consists in; stamping and pressing a sheet of metal into circular form with a 55 central dished portion and a peripheral flange; cutting away sections of said dished portion to form spokes and at the same time forming the rim of the wheel with a substantially semi-circular section to which said 60 flange is tangential; notching said flange at predetermined intervals; simultaneously die pressing the sections of said flange between notches transversely and longitudinally of each said section; and then die pressing the 65 flange sections transversely of the latter until the free edges of the notched flange sections engage with the inner edge of said semi-circular portion of the rim.

8. As an article of manufacture, a wheel- 70 like member having a plurality of spokes and an annular hollow rim, said spokes and rim leaving spaces each of which is bounded by a pair of spokes and a portion of the rim, said rim being circular in cross section taken 75 on a radial plane passing between any pair of spokes, all portions of said member being integrally formed from a single sheet of metal.

9. The process of manufacturing sheet 80 metal wheels and the like which consists in; providing a sheet of metal stamped and pressed into circular form with the rim comprising a curved portion and a flange portion, said flange portion being notched at 85 intervals therealong; then die pressing the flange portions of the rim so as to complete the circular cross section thereof.

In witness that I claim the foregoing I have hereunto subscribed my name this 24th 90 day of Jan. 1918.

ANDREW BENSON.
